UNITED STATES PATENT OFFICE.

WILLIAM R. PELTON, OF GRAND RAPIDS, MICHIGAN.

BOOT-TREE.

SPECIFICATION forming part of Letters Patent No. 883,480, dated October 1, 1901.

Assigned this 24 December 1900. Serial No. 40,859. (No model.)

To all whom it may concern.

Be it known that I, WILLIAM R. PELTON, a citizen of the United States, residing at Grand Rapids, in the county of Kent and State of Michigan, have invented certain new and useful improvements in Boot-Trees; and I do hereby declare the following to be a full, clear, and exact description of the invention, such as will enable others skilled in the art to which it appertains to make and use the same.

My invention relates to improvements in boot-trees, and more especially to such for forming and stretching felt boots in the process of manufacture.

Felt boots as usually manufactured are first made in blanks having the form of an elongated sack or bag open at the end forming the leg and rounded and closed at the end which is to form the foot. In the process of finally shaping these blanks upon a suitable tree or last they are subjected to considerable strain and stretch in parts and are liable to be made too thin in such parts or ruptured outright. The trees used for the purpose of so forming the blanks as usually made are objectionable, in that the part forming the front part of the foot and the part forming the heel are pivoted or otherwise connected to operate simultaneously, which makes the device hard to operate and liable to thin or rupture the blank in parts.

The object of my invention is to provide a device that will be easy of operation and that will not unduly stretch or rupture the blank, and to provide the same with certain new and useful features hereinafter more fully described, and particularly pointed out in the claims.

My invention consists, essentially, in providing the device with means whereby the parts operating upon the front part of the foot of the boot operate independently of the part operating upon the heel and leg of the boot and in certain details of construction and arrangements of parts, as will more fully appear by reference to the accompanying drawings, in which—

Figure 1 is a side elevation of a device em-

bodying my invention as it appears when closed to receive the blank; Fig. 2, the same in vertical section on the line 2 2 of Fig. 3, with the sole and instep parts in position for forming the forward part of the blank; Fig. 3, the same with all the parts in final position for forming the entire blank; Fig. 4, a detail in rear elevation of the mechanism for operating the parts; and Fig. 5 a plan view of Fig. 3, with the sole-piece and heel portion removed.

60

Like letters refer to like parts in all the figures.

A represents the front leg-section, having a portion opposite the foot longitudinally divided from front to rear by a slot C and provided with grooves C' at each side of the slot.

65

B is the rear leg-section, having one end B' to form the heel of the boot.

D is the sole-piece, which extends from the toe of the boot to opposite the end of the front leg-section A, to which it is pivoted, as at E. The toe of the sole-piece is pivoted to the toe of the instep-piece F, as at E', and the other end of the instep-piece is slidably connected to the front leg-section by being 70 extended within the slot C and provided with oppositely-projecting lugs G, engaging and traversing the grooves C'.

75

The rear leg-section B is movably connected opposite the foot portion to the front leg-section by means of a bell-crank lever H and connecting-rod I, by which the rear leg-section moves away from the front leg-section nearly horizontally and is held in extended position by said lever and rod. To this end 80 the lever H is pivoted to the rear leg portion at the fulcrum or angle of the lever and substantially opposite the instep of the boot. The forward arm of this lever extends into the slot C and is provided with oppositely-projecting lugs G', engaging and traversing the grooves C' above the lugs G on the instep-piece F. The other arm of the lever H is pivoted to one end of a connecting-rod I, as at I', the other end of said rod being pivoted 85 to the end of the front leg-section, preferably by the same pivot E on which the sole-piece turns.

85

90

95

The upper parts of the leg-sections A and B are provided with a brace J, pivoted to one of said sections, as at L, and having shoulders M engaging the other leg-section. To simultaneously turn this brace and the bell-crank, they are connected by a rod K, pivoted to each at its respective ends. The brace J may be manually operated, or it may be operated by any means commonly used for the purpose, the means for operating said brace constituting no part of my invention.

From the foregoing description of the construction the operation will be readily understood. When placed in the position shown in Fig. 1 and the blank placed theron, the lugs G and G' are in the upper ends of the grooves C'. The parts D and F are now operative independently of the leg-section and can be turned to the position shown in Fig. 2, thus breaking down and forming the front part of the foot without forming the heel or leg. This is easily done, requiring but little manual power. The brace J is now turned to a horizontal position by any suitable means and through the connecting-rod traverses the lugs G' down the grooves C'. The pivot II' moves downward relative to the pivot I' sufficient to properly neutralize the upward movement of the pivot I' as it traverses the are around the pivot E, thus carrying the rear section B nearly in a right line backward, which movement is best adapted to properly form the heel and leg and evenly distribute the stretch and strain on the blank. When fully opened out, as in Fig. 3, the lever II, rod I, and brace J securely and rigidly hold the rear leg-section in place, and the lugs G', engaging the lugs G securely hold the parts F and D from moving.

Having thus fully described my invention, what I claim, and desire to secure by Letters Patent, is—

1. In combination with a front leg-section, a rear leg-section, a sole-piece, and an instep-piece; means for movably connecting the rear leg-section to the front leg-section, and other means for movably connecting the sole-piece, and instep-pieces to said front leg-section, whereby the rear leg-section, and the sole and instep pieces may be separately operated, substantially as described.

2. In combination with a front leg-section, a sole-piece pivoted at the rear to the front leg-section, an instep-piece pivoted to the toe of the sole-piece at one end and slidably connected to the front leg-section at the other end, and a rear leg-section independently connected to the front leg-section, substantially as described.

3. The combination of a front leg-section having longitudinal grooves, a sole-piece pivoted to the end of the front leg-section, an instep-piece pivoted to the toe of the sole-piece at one end and having lugs traversing the grooves in the front leg-piece, a rear leg-

section, a lever pivoted to the same, lugs on the said lever traversing the said grooves, a brace pivoted to the rear leg-section, and a rod connecting the brace and lever, substantially as described.

4. The combination of a front leg-section, a rear leg-section, a bell-crank lever pivoted to the same and slidably connected to the front leg-section, a connecting-rod pivoted to the lever and front leg-section, a brace pivoted to one leg-section and slidably engaging the other leg-section, and a rod connecting the brace and lever, substantially as described.

5. The combination of a front leg-section, a sole-piece pivoted thereto, an instep-piece pivoted at one end to the toe of the sole-piece and slidably engaging the front leg-section at the other end, a rear leg-section, a lever pivoted to the same and slidably connected to the front leg-section and engaging and holding the instep-piece in position, substantially as described.

6. The combination of a front leg-section having longitudinal grooves, a sole-piece pivoted to the same, an instep-piece pivoted to the sole-piece at one end and having lugs traversing the grooves, a rear leg-section, a lever pivoted to the same and having lugs traversing the grooves and engaging the lugs on the instep-piece, and means for operating the lever, substantially as described.

7. The combination of a front leg-section having longitudinal grooves, a sole-piece pivoted to the same, an instep-piece pivoted to the sole-piece at one end and slidably engaging the front leg-section at the other end, a rear leg-section, a bell-crank lever pivoted to the same opposite the instep and having lugs traversing the grooves, a rod pivoted to the bell-crank lever and to the end of the front leg-section, a brace pivoted to the rear leg-section and slidably engaging the front leg-section, and a rod connecting the brace and lever, substantially as described.

8. The combination of a front leg-section having a longitudinal slot and grooves, a sole-piece pivoted to the end of the front leg-section, an instep-piece pivoted to the toe of the sole-piece at one end and extending within the slot at the other end, lugs on the same engaging and traversing the grooves, a rear leg-section, a bell-crank lever pivoted to the same and extending within the slot, lugs on the same engaging and traversing the grooves and engaging the lugs on the instep-piece, a connecting-rod pivoted to the bell-crank lever and to the end of the front leg-section, and means for operating the said lever, substantially as described.

9. The combination of a front leg-section having longitudinal slot and grooves, a sole-piece pivoted to the same, an instep-piece pivoted to the sole-piece and extending within the slot, lugs on the instep-piece engaging and

traversing the grooves, a rear leg-section, a bell-crank lever pivoted to the same opposite the instep and extending within the slot, lugs on the lever engaging and traversing the

5 grooves and engaging the lugs on the instep-piece, a connecting-rod pivoted to the lever and to the end of the front leg-section, a brace pivoted to the rear leg-section and having shoulders slidably engaging the front leg-

section, and a rod connecting the brace and 10 lever, substantially as described.

In testimony whereof I affix my signature in presence of two witnesses.

WILLIAM R. PELTON.
